UNITED STATES PATENT OFFICE.

WILLIAM RAPHAËL BOISVERT, OF ST. DAVID DE LEVIS, QUEBEC, CANADA.

BED-SPRING.

No 874,048.

Specification of Letters Patent.

Patented Dec. 17, 1907.

Application filed February 7, 1907. Serial No. 356,261.

To all whom it may concern:

Be it known that I, WILLIAM RAPHAËL BOISVERT, a subject of the King of Great Britain, residing at St. David de Levis, 5 county of Levis, in the Province of Quebec, Canada, have invented certain new and useful Improvements in Bed-Springs; and I do hereby declare that the following is a full, clear, and exact description of the invention, 10 such as will enable others skilled in the art to which it appertains to make and use the same.

My invention relates to bed springs; the object of my invention is to provide a bed 15 spring which is flat and which may be tensioned, loosened, or removed independently of the other springs forming part of the set of springs, so that the whole set may be packed in a small space; a further object 20 is to provide means for adjustably attaching the spring to an ordinary form of bed frame; and, my invention consists of the construction, combination and arrangement of parts, as herein illustrated, described and 25 claimed.

In the accompanying drawings, forming part of this application, I have illustrated one form of embodiment of my invention, in which drawings similar reference characters 30 designate corresponding parts, and in which:

Figure 1 is a plan view; Fig. 2 is a side elevation of a single spring; Fig. 3 is an enlarged side elevation of a single spring; Fig. 4 is a plan view.

Referring to the drawings, 1 designates a broad flat spring, which is slightly crimped or corrugated to increase its elasticity, and which has formed on its ends hooks 2.

Removably attached to the hook 2 adjacent the foot end member C of the bed frame, 40 is a hook 3, adapted to fit over the usual angle iron frame C.

Disposed transversely of the side frame members A, and parallel to and adjacent the head frame member B of the bed, is a bar 45 5, to which is secured the ends of yokes 6, which yokes are adapted to be engaged by the hooks 2 formed on the springs 1.

Hooked members 7 are provided with the screw-threaded body 8, which is disposed 50 through the bar 5 and adjustably maintained thereon by means of the nuts 9. The hooked members 7 are disposed over the head bed frame member B, so that the bar 5 may be adjusted towards or away from the 55 frame to increase or decrease the tension on the springs 1.

Having thus fully described my invention, what I claim as new, and desire to secure by Letters Patent, is:—

A bed spring comprising a flat corrugated body, hooks integrally formed on the opposite ends thereof connections between the hooks on one end of the spring and the framework of the bedstead, a spring loop removably secured to the other of said hooks, an adjusting bar, resilient arms extending from said loop and engaging said bar, and means for adjustably connecting said bar to the framework of a bedstead.

In witness whereof I have hereunto set my hand in the presence of two witnesses.

WILLIAM RAPHAËL BOISVERT.
